(57) CLAIM

The ornamental design for a horizontal cigarette-making machine, as shown and described.

DESCRIPTION

FIG. 1 is a front perspective view of a horizontal cigarette-making machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The structural features depicted by broken lines in the drawing views have been shown for the purpose of illustrating portions of the horizontal cigarette-making machine that form no part of the claimed design.
